UNITED STATES PATENT OFFICE.

EDWARD H. ANGIER, OF QUINCY, MASSACHUSETTS.

CORRUGATED SHEET.

1,025,443.

Specification of Letters Patent.

Patented May 7, 1912.

Application filed February 11, 1911. Serial No. 607,897.

To all whom it may concern:

Be it known that I, EDWARD H. ANGIER, a citizen of the United States, and a resident of Quincy, in the county of Norfolk and 5 State of Massachusetts, have invented an Improvement in Corrugated Sheets, of which the following description, in connection with the accompanying drawings, is a specification, like letters on the drawings 10 representing like parts.

This invention is an improvement in corrugated composite sheets which may be used in making boxes and for other closures or purposes.

15 The character of the invention may be best understood by reference to the following description of an illustrative embodiment thereof shown in the accompanying drawing, wherein:

20 Figure 1 is a plan view of a portion of a composite sheet embodying the invention, parts being broken away; Fig. 2 is a side elevation of the sheet shown in Fig. 1; and Fig. 3 is a perspective view of a box made 25 of a composite sheet embodying the invention.

I will first describe the composite sheet and then a use thereof as typified by the box shown in Fig. 3.

30 Referring to Figs. 1 and 2, 1 designates a layer of corrugated paper or other material constituting the body of the sheet; 3, 3 designate wear-resisting layers on opposite sides of said corrugated layer of textile or 35 reticulated fabric or other suitable material, preferably woven, the material shown herein being conveniently of commercial burlap.

5, 5 designate intermediate flat or sheet-like layers of paper or other suitable material interposed between the corrugated layer 1 and the textile layers 3, 3. These intermediate layers are suitably secured to the opposite faces of the corrugated layer as by 40 an adhesive. The intermediate layers may 45 be of waterproof material or on their faces contiguous to the textile layers there may be supplied a waterproof coating of asphalt, or other suitable waterproof material which, if desired, may constitute the adhesive for 50 securing the textile layers to said intermediate layers.

In making a composite sheet such as described, the textile fabric will be pressed or embedded more or less into the adhesive or 55 waterproof coating of the flat paper sheets and, as a result, the threads of the fabric

will be individually, securely held to the said paper layers.

A sheet composed of layers such as described, presents a very advantageous construction. The corrugated layer contributes stiffness to the sheet which is supplemented by the flat paper layers conjoined to the opposite faces thereof, said layers constituting effective binders for securing the burlap 60 to the corrugated paper. The textile layers which constitute the exterior faces of the sheet add to the strength of the latter and present effective wear-resisting surfaces. The inherent flexibility of the asphalt waterproof material and the flexibility of the fabric prevent cracking of the waterproof material. The fibers or threads of the fabric preferably project above the face of the waterproof material and present a clean, 70 non-adhesive fabric surface protecting the waterproof material and preventing any possibility of the latter being scraped from the paper layer. If the corrugated paper layer becomes wet the corrugations thereof 75 will tend to flatten and become ineffective as stiffening members. One great advantage of the waterproof layer is to effectively protect these corrugations from moisture.

While the sheet shown herein includes 80 textile layers on opposite sides of the sheet it will be understood for many purposes it will suffice to have a fabric layer on but one and preferably the exterior side of the sheet.

Having described the sheet material, I will now describe a use thereof with more particular reference to Fig. 3 wherein is shown a box or carton comprising sides 7 and ends 9 formed of one continuous strip preferably 90 having the corrugations of the sheet extending vertically, thereby permitting the sheet to be more readily scored and bent to form the corners of the box. The composite sheet adapts itself readily to the formation of a 100 tight union at the juncture of the ends of the sheet as well shown in Fig. 3 wherein the outside paper and textile layers are together extended beyond the corrugated layer to provide a margin 11 overlapping the end of 105 the box, said margin being secured thereto by an adhesive, or otherwise, as desired. By this construction it is not necessary to use an additional strip of cement tape or other material to secure the meeting edges together, 110 but the latter are securely retained by portions of the main body of the sheet of which

the box is formed. The cover and bottom of the box may be formed of opposed end and side flaps 13, 15, folded over and, if desired, of an extent to meet one another. The 5 overlapping end and side flaps constituting the cover and bottom of the box may be secured together by an adhesive.

A box formed of the composite waterproof sheet material described presents a number 10 of advantages. The corrugated layer and paper layers together provide sufficient stiffness to cause the box to permanently maintain its shape, the waterproof sheet prevents the ingress of water to the interior of the 15 box, while the burlap exterior covering presents a strong, durable, wear-resisting surface.

A carton having some of the features of the box described herein, is disclosed and 20 claimed in my co-pending application, Serial No. 649,806.

Having described preferred embodiments of the invention without limiting myself thereto, what I claim as new and desire to 25 secure by Letters Patent, is:

1. A composite sheet comprising a layer of corrugated stiffening material, a sheet-like waterproof layer secured to the ridges of the corrugations, and a wear-resisting 30 layer of textile fabric applied to said waterproof layer for protecting the same.

2. A composite sheet comprising a layer of corrugated stiffening material, a sheet-like waterproof layer secured to the ridges 35 of the corrugations, and a wear-resisting fabric layer in adhesive engagement with said waterproof layer for protecting the same.

3. A composite sheet comprising a layer 40 of corrugated stiffening material, a sheet-like waterproof layer secured to the ridges of the corrugations, and a reticulated fabric layer applied to said waterproof layer for protecting the same.

45 4. A composite sheet comprising a layer of corrugated stiffening material, a sheet-like waterproof layer secured to the ridges

of the corrugations, and a fabric layer applied to said waterproof layer and presenting a fabric wear-resisting surface.

50

5. A composite sheet comprising a layer of corrugated stiffening material, a sheet-like waterproof layer secured to the ridges of the corrugations, and a protective fabric layer having fibres thereof somewhat embedded in the waterproof material of said waterproof layer.

55

6. A composite sheet comprising a layer of corrugated stiffening material, a sheet-like layer secured to the ridges of the corrugations and having a waterproof coating of asphalt, and a burlap layer applied to said waterproof coating for protecting the same.

60

7. A composite sheet comprising a layer of corrugated stiffening material, a sheet-like waterproof layer secured to ridges on one side of said corrugated layer, a wear-resisting fabric applied to said waterproof layer for protecting the same, and a layer of textile fabric for protecting the opposite side 70 of said corrugated layer.

65

8. A composite sheet comprising a layer of corrugated stiffening material, a sheet-like waterproof layer secured to the ridges at one side of said corrugated layer, a wear-resisting fabric layer applied to said waterproof layer for protecting the same, and a sheet-like layer secured to the ridges at the 75 opposite side of said corrugated layer.

75

9. A composite sheet comprising a layer 80 of corrugated stiffening material, sheet-like waterproof layers secured to the ridges at the opposite sides of said corrugated layer, and wear-resisting fabric layers applied to said waterproof layers for protecting the 85 same.

In testimony whereof, I have signed my name to this specification in the presence of two subscribing witnesses.

EDWARD H. ANGIER.
